(57) **CLAIM**

The ornamental design for a pump base, as shown and described.

DESCRIPTION

FIG. 1 is a front perspective view of a pump base having portions shown in phantom;

FIG. 2 is a front view thereof;

FIG. 3 is a right side view thereof;

FIG. 4 is a top plan view thereof;

FIG. 5 is a left side view thereof;

FIG. 6 is a bottom plan view thereof; and,

FIG. 7 is a rear view thereof.

The elements shown in phantom form no part of the claimed design. The rear view of the pump base is the same as the rear view of the assembled pump base and pump and therefore is not separately illustrated.
